US0D1066696S

(12) **United States Design Patent** (10) Patent No.: **US D1,066,696 S**
(45) Date of Patent: ** Mar. 11, 2025

(54) **HEADREST OF A MEDICAL HEAD
IMMOBILIZER**

(71) Applicant: **SEOUL NATIONAL UNIVERSITY
HOSPITAL**, Seoul (KR)

(72) Inventors: **Dong Keon Lee**, Seongnam-si (KR);
Dae Kon Kim, Seongnam-si (KR)

(73) Assignee: **Seoul National University Hospital**,
Seoul (KR)

(**) Term: **15 Years**

(21) Appl. No.: **35/518,330**

(22) Filed: **May 17, 2023**

(80) **Hague Agreement Data**

Int. Filing Date: **May 17, 2023**

Int. Reg. No.: **DM/231200**

Int. Reg. Date: **May 17, 2023**

Int. Reg. Pub. Date: **Sep. 15, 2023**

(30) **Foreign Application Priority Data**

Nov. 24, 2022 (KR) 30-2022-0048970
